UNITED STATES PATENT OFFICE.

WILLIAM SPENCER, OF CHEBOYGAN, MICHIGAN.

GRAPPLE.

SPECIFICATION forming part of Letters Patent No. 336,498, dated February 16, 1886.

Application filed October 18, 1884. Serial No. 145,863. (No model.)

To all whom it may concern:

Be it known that I, WILLIAM SPENCER, a citizen of the United States, residing at Cheboygan, in the county of Cheboygan and State 5 of Michigan, have invented certain new and useful Improvements in Grapples; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

15 My invention has relation to spring grapples or holders for various purposes; and the object of the device is to provide a means for grappling and holding all kinds of articles to which it is adapted; and the novelty consists 20 in the construction of the grapple itself, as will be hereinafter more fully described, and particularly pointed out in the claim.

25 The figure in the drawing is a perspective representation of my improved spring-grapple.

The grapple consists of a spring-wire frame, made of a single piece of wire of suitable size and dimensions to correspond to the use to which it is intended to apply it.

30 A A are the sides, and are approximately parallel, having their lower ends bent inwardly at a right angle, to form the prongs a. The top B is somewhat arch-shaped, and its center is formed into a link, C, for securing a 35 screw or eyebolt, c. This link C forms a spring, and allows the arms or sides A A to spring outwardly, so that the prongs a will spread and engage the article to be held, and when it is desired to release the article it can 40 be readily done by springing the sides A A apart with the hands, so as to disengage the prongs a a.

The various uses to which my invention can be applied will readily suggest themselves, and it will be found an article of general household utility, being very convenient for holding and carrying boxes and bundles, as well as packages of various shapes and sizes, spools of cord and rope, rolls of water-closet paper, coils of twine, ribbon, and the like, towel-rollers, and a variety of other uses, so that further description is unnecessary.

In the device for holding spools shown in patent to Claybrook a hook is used for attaching the device to a lady's dress or belt, and if 55 it were to be secured to the wall a staple or hook of some kind would have to be used. In my case the screw-eye can be detachably secured to any permanent fixture, or it can be used as a hook when necessary; and it will thus 60 be seen that the frame acts as a handle or lever in securing the screw-eye, so that no tool is required when the device is attached or detached.

Having thus described my invention, what 65 I claim as new and useful, and desire to secure by Letters Patent of the United States, is—

The frame B, made of a single piece of spring-wire, having the sides A A, projecting downward and terminating in right-angled arms a a, and having the link C, provided with the screw-eye c, whereby the said frame B will also form a handle for inserting the screw-eye, as set forth.

75 In testimony whereof I affix my signature in presence of two witnesses.

WILLIAM SPENCER.
